UNITED STATES PATENT OFFICE.

EDWIN RICHARD MUMFORD, OF DUMBARTON, SCOTLAND.

AERODROME OR FLYING-MACHINE.

No. 892,380.

Specification of Letters Patent.

Patented June 30, 1908.

Application filed July 11, 1906. Serial No. 325,711.

To all whom it may concern:

Be it known that I, EDWIN RICHARD MUMFORD, a subject of the King of Great Britain and Ireland, and a resident of Dumbarton, in the county of Dumbarton, Scotland, have invented certain new and useful Improvements in or Connected with Aerodromes or Flying-Machines, and of which the following is a specification.

10 This invention relates to aerodromes or flying machines heavier than air, and of the type described in my patent application Serial No. 300,752. In the apparatus therein described a comparatively large number of 15 propellers of more or less specific pitch and areas and driven at a specifically proportionate speed are used for both suspension and propulsion and are so arranged that their inclination relatively to the body of the apparatus is capable of variation.

20 The present invention has for its object to retain the advantages of this form of apparatus while simplifying and reducing the weight, and to provide more effectively against certain contingencies.

25 According to my present invention the axes of the propellers are fixed relatively to the plane of what may be termed the hull of the apparatus and are either at right angles thereto or are inclined (their degree of inclination being fixed) as may be found most convenient under particular conditions and their inclination to the vertical to the degree requisite to bring about the conditions hereinbefore referred to is brought about by the 30 inclination in the direction of its length of the whole apparatus. This inclination is brought about by a rudder (or rudders) acting in a horizontal plane. The action of the rudder 35 may be assisted by the longitudinal moving of a weight (say the operator's).

40 In carrying out my invention, the hull of the aerodrome is a light framework, of bamboo, aluminium, or other suitable material, 45 provided with means for carrying the motor or motors driving the propellers and for accommodating the operators. Horizontal adjustable rudders, consisting of light but rigid frames upon which is laced suitable textile 50 material, may be arranged upon horizontal axes at one end or at both ends of the hull framework. There may be one of these horizontal rudders preferably at the after end or there may be one at each end, and they are 55 so positioned and formed as to offer little re-

sistance to the downward flow of air from the propellers. In operation, these rudders, or that rudder when there is but one, are so inclined from the horizontal in the direction of the length of the apparatus that the reaction (due to the horizontal movement of the apparatus) of the air on them (or on it) is such as to incline the whole apparatus to an extent to give the inclination from the vertical to the propeller axes requisite to give the desired more or less horizontal direction of flight to the apparatus. In addition to this function the horizontal rudder (or rudders) and plane surfaces (if there be such) serve to balance the apparatus and to afford a certain degree of additional safety should the propelling machinery break down.

60 A rudder (or rudders) upon a vertical axis is also provided under control of the operator for steering in a horizontal plane, if 65 there be but one it is preferably at the after end of the apparatus. Preferably, however, I use a known form of rudder capable of causing bodily inclination and to some extent also bodily lateral movement of the apparatus and also simultaneously of steering 70 it in a horizontal plane. This form of rudder, 75 consists of a framework of triangular, truncated triangular (that is to say, trapezoidal) rectangular, or other convenient 80 form, carried at its apex (or corresponding point when it is of form other than triangular) upon an axis in the framing of the apparatus and at one end of it. The framework 85 may be made to a certain extent flexible or 90 preferably and more conveniently the joint of its connection to the apparatus may be a ball-and-socket, "Hooke's", or other universal joint, but in any case such that the member, at the base (it being assumed for convenience in description that the framing is 95 triangular) is capable of angular movement relatively to the apex and of lateral or vertical movement or conjoint lateral or vertical movement about the apex as a fixed point 100 and it is covered with textile fabric secured to it by lacing. Means under control of the operator are provided for turning the framing about its axis; that is;—turning it relatively to the plane of the whole apparatus; or for inclining it (i. e. moving it vertically 105 about the joint) or for moving it laterally the means preferably being such that the various movements may be made either conjointly or separately as may be desired.

When the framing is moved vertically, that is, if its outer part be raised or depressed and its median line still be maintained in the vertical plane of the apparatus it acts only 5 to control the inclination of the apparatus in a horizontal plane. If it be turned about its axis so that its surface becomes inclined to the horizontal plane of the apparatus while its median line remains in the vertical plane 10 it acts to steer the apparatus in a horizontal plane. If, in addition to this last movement it be moved laterally about its pivot so that its median line is no longer in the vertical longitudinal plane it has a further and more 15 effective steering effect in the horizontal plane as its outboard unbalanced weight then tends to tilt the apparatus as a whole to the side to which it is inclined. It is clear that guidance in a horizontal plane and vertically may be accomplished simultaneously 20 by these conjoint movements of this form of rudder.

The combined suspensory and propulsive screw propellers are arranged above the hull 25 upon shafts which are either of a fixed degree of inclination to the plane of the latter or which are vertical. There are at least two equal propellers, or there may be any convenient multiple of two, one half of their 30 number being right-handed and the other half left-handed so as to eliminate any horizontal turning couple, or the propellers may be otherwise proportioned and arranged to this end. The propeller shafts are driven 35 through suitable gearing from a motor or motors operated by any suitable power (for example, combustible vapor or gas) and preferably arranged below the propellers so that the whole weight of hull, motors, and 40 operators is below the suspensory propellers, *i. e.* the point of suspension of the apparatus when it is in the air.

In order to increase the stability of the apparatus when in flight the axes of the propellers may be so inclined to one another 45 that when produced they pass through a point either above or beneath the apparatus and so that the lines of reaction of the various propellers are not parallel to one another.

In operation, whether the apparatus merely rise vertically, rise vertically and move horizontally coincidently—*i. e.* proceed in a plane inclined to the horizontal—or 55 move horizontally, is entirely dependent upon the angle in the direction of horizontal movement to the horizontal plane which the axes of the propellers are constrained to assume by the lengthwise inclination of the apparatus as a whole, and this lengthwise inclination is brought about by the reaction of the air upon the horizontal rudders. Consequently, the apparatus is directed in flight in 60 any direction by manipulating the rudder device.

The propeller shafts may be so positioned that the paths of the propeller blades overlap, the propellers being so geared together, and the position of their blades being so adjusted, that they do not foul one another in 70 rotating. As the propellers may then be arranged much closer together considerable weight is saved in hull, and advantage is thus gained notwithstanding the possible slight loss of efficiency in the propellers due 75 to the overlapping of their paths.

In order that the invention may be more readily understood there are hereunto appended two sheets of explanatory drawings, Figure, 1, Sheet, 1, and Figs. 2, and 3, Sheet, 80 2, being, respectively, a plan, a side elevation and an end elevation all diagrammatic of an example of the improved aerodrome provided with six propellers arranged at a fixed inclination to the hull or framing of the 85 apparatus—like parts being indicated through out by like reference letters.

Since the general construction of the propellers and framing is substantially similar to that described in my said earlier patent 90 specification, hereinbefore referred to, it is unnecessary to enter minutely into the structure of the apparatus.

The six propellers, A, are carried upon shafts, B, which, as will be seen clearly in 95 Fig. 2, are inclined to the vertical in a longitudinal direction, that is to say, they are inclined and not at right angles to the general plane of the framing or hull, C. The shafts, B, are driven from longitudinal shafts, D, 100 by bevel gearing and the shafts, D, are in their turn driven from two petrol motors, E, by pitch chains. The motors, E, (which rotate reversely) are as will be seen in Fig. 3, interconnected by two pitch chains, F, each 105 gearing with a sprocket wheel upon their respective driving shaft and with a sprocket wheel upon shafts, R, carrying upon them spur wheels, S, gearing with one another. The speeds of the two motors and of the 110 whole gearing and propellers are thus absolutely synchronized as is obviously necessary in view of the arrangement of the last in the present example, and, at the same time, one motor is able to carry on the drive of all propellers at a reduced speed should the other 115 break down. The motors, E, are carried upon a slat framing or platform, G, which also serves as a platform for the operators. In this example a single rudder, H, of triangular 120 section attached by a ball joint at its apex to the rear of the framing, C, is employed. It is operated by yoke lines, J, K, attached above and below it on its right-hand side and like lines, L, M, on its left-hand side. The upper 125 lines, J, L, pass over guide pulleys, N, on the framing to drums or other devices for operating them conveniently situated upon the platform, G. The lower lines, K, M, pass over pulleys carried on brackets, O, to the 130

130

operating devices. The operating devices are such that one of each pair of lines, J, K, and L, M, is paid out at the same speed as the other is hauled in so that the pairs of lines are always taut and so hold their side of the rudder rigidly in all positions. Further, the device is such that either pair may be operated separately or both together. It is further necessary—in order to incline the rudder laterally—that either pair of lines may be paid out conjointly, while the other pair is being hauled in. Such a device may very well consist of a number of drums upon which the various lines are wound and is obviously besides being capable of wide variation capable of being applied, by anyone skilled in the art, it is therefore not more particularly described.

In order that the length and width of the apparatus and consequently its weight may be as small as possible with a given propeller diameter, the propeller shafts, B, are placed at such a distance apart both longitudinally and transversely that the paths of the propeller blades, A, overlap; the propellers being so geared together and the positions of their blades being so adjusted that they do not foul one another in rotating. This is clearly seen in Fig. 1, adjacent propellers—which, of course, have only two blades—being set with the median line at right-angles.

In order to increase the stability of the apparatus when in flight the axes of the propeller shafts, B,—which are parallel with each other in a longitudinal direction—are so inclined transversely upon opposite sides of the apparatus and as shown in Fig. 3, that the axes of transversely opposite pairs meet, when produced, in points beneath the longitudinal center line of the apparatus. Thus the lines of reaction of the two sets of propellers upon either side are not parallel with each other. To the same end, the axes may be so inclined as to meet in points above the apparatus.

It is not necessary when the apparatus is designed for flight in contradistinction to mere ascension that the axes of the propellers should also be inclined towards each other longitudinally but where the apparatus is designed for ascension only they may be thus inclined; that is to say, the axes of all the propellers may pass when produced through a point either above or beneath the apparatus.

Instead of inclining the propeller shafts longitudinally to the plane of the apparatus as a whole they may be arranged at right-angles thereto, the inclination of the apparatus as a whole either by the movement of weights, or of its rudder, or rudders, having the same effect as if the apparatus be maintained horizontal and the propeller shafts be inclined.

It is to be understood that the numbers, pitch, areas, and speed of the propellers are

to be devised in accordance with the general directions contained in the specification of my earlier patent hereinbefore referred to. The factors in this direction are obviously to a certain extent interdependent; but it may be stated broadly that, for propellers of given diameter the efficiency of thrust per power depends mainly upon the ratio of pitch to diameter, and upon the ratio of surface blades to the total area of disk traversed by the blades—both these factors should be within certain limits. For similar propellers, the efficiency of thrust for a given power increases with increase of diameter.

It has been found by actual test that flight can be accomplished with a certain minimum of ratio of total disk area of propellers to the total weight to be lifted, which ratio depends upon the designed degree of lightness and strength of the propellers, and upon the power per weight of engine or engines. It has also been found that for a given suitable design there is a higher limit of ratio of total disk area to total weight, beyond which the gain in efficiency of thrust per power, due to increase of total disk area, is not sufficient to compensate for the extra weight due to increasing the total disk area. In machines of suitable light and strong construction, the limits of ratio of total disk area to total weight and power may be relatively far apart, and in such cases the margin of lifting force (and therefore acceleration of upward movement) is at its maximum midway between the limits. In machines of heavier design the limits are narrowed, and the margin of lifting force is relatively reduced. And it is obvious that if the design be too heavy flight will be impossible for any ratio of disk area to total weight.

The example given in the former specification is one that fulfills the conditions necessary to accomplish flight, and is here repeated as typical:—In a machine having a total weight of hull, motor, gearing, and load not exceeding 900 lbs. six propellers are used each of a diameter of about 25 feet, each of about 25 feet pitch, and each having a horizontally projected area of about 125 square feet (the total disk area—that is, the area covered by the blades when revolving—being in all about 2950 square feet, while the total flat area—i. e. the area of one side of the blades—is in all about 1,000 square feet, this area projected on the plane of revolution being about 750 square feet). These six propellers are driven at about 40 revolutions per minute by motors (or a motor) weighing in all about 250 lbs. and developing about 30 H. P. Thus it will be seen that for each pound of total load raised, the disk area of the propellers is about 3 square feet, the flat area of the blades is fully one square foot and their area projected on the plane of rotation is fully 0.8 of a square foot, while the power

provided per pound of load is $\frac{1}{30}$ th H. P. This for ascension, for horizontal flight much less power is necessary.

What I claim is:—

1. The combination in an aerodrome having a plurality of propellers acting both for suspension and propulsion, shafts carrying said propellers arranged in pairs upon opposite sides of the apparatus, said opposite shafts being inclined downwardly, backwardly and towards each other so that if produced their axes would meet in a longitudinal line beneath the apparatus.
- 10 2. The combination in an aerodrome having a plurality of propellers acting both for suspension and propulsion, shafts carrying said propellers arranged in pairs upon oppo-

site sides of the apparatus, said opposite shafts being inclined downwardly, backwardly and towards each other so that if produced their axes would meet in a longitudinal line beneath the apparatus, and a rudder for said apparatus comprising a triangular framework and covering therefor, a universal joint at the apex, and means for moving said 25 rudder about said joint.

In testimony whereof I have signed my name to this specification, in the presence of two subscribing witnesses.

EDWIN RICHARD MUMFORD.
